TRANSFER MECHANISM

Max M. Kipfer, New Kensington, Pa., assignor to
Aluminum Company of America, Pittsburgh,
Pa., a corporation of Pennsylvania

Application August 9, 1947, Serial No. 767,794

6 Claims. (Cl. 93—60)

1

This invention relates to a transfer device and particularly to a device for transferring cup-shaped articles of thin sheet material, such as metal foil. The invention is especially useful in manufactures requiring transfer of thin cup-shaped articles from one forming station to another. An example of this is found in the manufacture of pleated foil bottle capsules wherein a first set of dies forms a foil capsule with a loosely pleated skirt and a second set of dies flattens the pleats to complete the capsule.

The manufacture of these pleated foil capsules, as it has been practiced, is described in the U. S. patents to Bruun 2,017,054 and Jensen 2,131,438. The apparatus of the Bruun patent consists essentially in a stationary male die and a reciprocating female die, which have complementary grooves and cooperate to cut and form a foil blank into a capsule with a pleated skirt. This capsule may then be completed by smoothing and flattening the pleats by means of a stationary female die and reciprocating male die, as disclosed by Jensen.

The open pleats and the foil capsule itself following the first operation are susceptible to damage by ordinary handling means, and it has been the practice to allow the pleated capsules to fall free from the pleating dies without orienting them for proper presentation to the flattening dies. This interjects a manual operation so that the pleating and finishing dies are in separate installations.

It is an object of this invention to provide automatic means for transferring thin gauge fragile articles from a forming station. More particularly, it is an object of the invention to provide means operating to receive such articles at a forming station and present them in proper orientation at a second forming station. It is another object to provide a transfer and orienting device particularly adapted to the production of thin pleated capsules, and it is to this adaptation that the following description relates. This description, from which other and further objects and advantages will appear, refers to the accompanying drawings, in which:

Fig. 1 is a view in elevation showing the arrangement of the pleating and finishing dies when the improved transfer device is used;

Fig. 2 is a plan view on a larger scale of the pleating machine and associated parts of the transfer device;

Fig. 3 is a view in side elevation on a still larger scale, showing the reciprocating assembly of the pleating machine;

2

Fig. 4 is a view on the line 4—4 of Fig. 2 looking in the direction of the arrows and on a larger scale;

Fig. 5 is a vertical sectional view through the cam which operates the transfer device and showing the cam roller in retracted position; and

Fig. 6 is a horizontal sectional view through the pleating dies.

The pleating mechanism is supported on a bed 7 which in turn is supported on a frame 8 substantially above the level of support 9 for the finishing mechanism. The male pleating die is indicated generally at 10 and the female pleating die at 11. The female die is secured to ram 12, which is connected by coupling 13 with connecting rod 14, connected in turn to eccentric 15 on drive shaft 16. This shaft is supported on an extension of the bed 7 and is driven by any suitable means from motor M, and sprocket 17 on shaft 16, sprockets 18 and 19 and chains 20 and 21 serve to actuate turntable 22 carrying the female finishing dies 23. A single male die or punch (not shown) cooperates successively with these female dies to flatten the pleats. Preferably this male die is located over a point on the turntable removed from the location of delivery tube 24 to permit inspection of the capsules for proper seating in the female dies before, and final inspection and removal of the capsules by any suitable means (not shown) after, the finishing operation.

The reciprocating assembly carrying the female die 11 is supported on the slide 25 and includes in addition to the die, ram and coupling, a cam roller and a knockout assembly. The cam roller 26 (Figs. 3 and 5) is mounted on the end of stud 27 (Figs. 2 and 5) which is secured as by welding in a block 28 secured to the side of the ram as by bolts 29. The knockout assembly is carried by a plate 30 bolted to the top of the ram. Secured to the plate at either side of the ram as by bolts 31 are brackets 32 (Figs. 3 and 4) in which rods 33 carrying adjusting screws 34 are slidably received. Also secured to the plate 30 at either side are brackets 35 upon which levers 36 are pivoted by screws 37, and the upper ends of the levers are connected by tie rod 38. Air cylinder 39 secured to the top of the plate 30 has a piston 40 and is connected to an air line 41 which leads from any suitable type of valve 42. This valve, shown in Fig. 4, is located adjacent to the shaft 16 and is arranged to operate with each machine cycle.

Supported on the bed 7 to one side of and with its axis parallel to that of the ram 12 is a preferably cylindrical cam 43, which has a cam track

in the form of a slot 44 adapted to receive the aforescribed cam roller 26. The cylindrical cam is supported by shafts 45, 46 turning in bearings the housings 47 of which are bolted to the bed 7, and the shaft 46 extends substantially beyond its bearing. The hub 48 of arm 49 is secured on the extended shaft 46, and at its other end the arm carries a member 50 in the form of a truncated cone. This member is hollow and its side and end walls are apertured, as shown at 51 (Fig. 10 2). Hub 48, arm 49 and cone 50 may be made separately and secured together as by peening, welding, upsetting, etc.

The delivery tube 24 is supported by the frame 8 with its upper end extending within the bed 7 below and to the side of the center line of the slide 25, the centers of the delivery tube entrance and of the female die coinciding with the extremes of an arc centered at shaft 46 and equal in degrees to the circumferential extent of slot 44 in cam 43. It will be understood that an oscillatable member other than the cylindrical cam shown may be used and the same result achieved by changing the form of the cam slot or relocating the delivery tube. An air line 52 is positioned with an aperture 53 adjacent its closed end in line with the open end of tube 24.

The male pleating die 10, mounted in a housing 54 bolted to an extension of the bed 7, carries the shearing edge 55 and includes a stationary mandrel 56 and an annulus 57 carried on rods 58, 59 which are held yieldably in the position shown in Fig. 6 by suitable means such as springs. Both the annulus and the mandrel are grooved as shown at 60. A stripper plate 61 is mounted in front of the male die.

The female die 11 carries an annulus 62 having a shearing edge 63. The main die portion 64 has grooves 65 complementary to the grooves 60. The center of the die is formed by an ejector 66 sliding in sleeve 67 and carrying pin 68 extending through slots 69 in said sleeve 67. Springs 70 tend normally to hold the ejector 66 in retracted position, the advanced position shown in Fig. 6 being the result of action of the knockout assembly, as will be described.

The operation of the improved apparatus will be readily understood. With the reciprocating assembly retracted, a strip of foil from a roll (not shown) is fed behind the stripper plate 61, or between housing 54 and plate 61 as viewed in Fig. 6. The roller 26 is then in the position shown in Fig. 5 and as the reciprocating assembly begins its forward movement the roller bears upon the lower wall of the slot 44 turning the cam 43 counterclockwise as viewed in Fig. 4 and swinging arm 49 until cone 50 is in line with the open end of tube 24, and between said open end and aperture 53. Continued movement of the reciprocating assembly carries the shearing edge 63 past the stripper plate 61 so that this edge cooperates with shearing edge 55 to cut a round blank from the foil strip. As the annulus 57 is moved against the yielding support for rods 58, 59 and the mandrel 56 remains stationary, the ejector 66 being retracted, the male and female dies form a pleated cup shaped blank. On retraction of the reciprocating mechanism, the roller 26 travels in the straight portion of slot 44 until the dies are completely disengaged. Approaching the end of the retracting movement the roller bears against the upper wall of slot 44 and turns the cam clockwise as viewed in Fig. 4, swinging arm 49 until the cone 50 is in position between the

male and female dies. At that time air is admitted to cylinder 39 projecting piston 40 against the tie rod 38 and swinging levers 36 to bring their free ends against rods 33 to project the heads of adjusting screws 34 against pin 68. This position of the parts is that shown in Figs. 1 and 2. This action thrusts the ejector 66 forwardly to the position shown in Fig. 6 to place the pleated capsule on the cone 50. At the beginning of the advancing stroke the roller 26 again bears on the lower wall of the cam slot to again swing the arm to bring the cone carrying the pleated capsule in line with a constant or timed air blast from aperture 53 which dislodges the capsule and directs it, closed end first, into tube 24. The successive capsules fall from the lower end of tube 24 in this same orientation and are properly positioned in the finishing dies 23.

Admission of air to the cylinder 39 from the valve 42 is substantially instantaneous, and immediately after actuation of the knockout device, the ejector 66 and rods 33 are retracted by springs 70, which, however, may be dispensed with, as the same action would result, although at a later point in the cycle, by reason of the stationary mounting of mandrel 56.

It will be seen that throughout the travel of roller 26 in the straight portion of cam slot 44, the cone 50 dwells at its lower position. Oscillation of the cone 50 into and out of the capsule receiving position is controlled by travel of the roller in the curved portion of the slot or at the end of the retracting stroke and at the beginning of the advancing stroke. Movement of the cone is accordingly relatively rapid, and the action of the knockout assembly is timed to occur at substantially the instant of full retraction. The pleating dies accordingly are completely disengaged throughout action of the transfer device.

It will be understood that while it has been elected to illustrate the transfer device in connection with the manufacture of pleated capsules in which it is particularly useful, the invention is adaptable to other manufactures as well, and will be found to be of advantage in any manufacture of cup shaped articles in more than one operation. And although the invention is of most practical value where such articles are thin walled or otherwise delicate, it is not limited in that respect. Moreover various modifications of construction are contemplated within the invention, which is limited only as defined in the appended claims.

I claim:

1. In apparatus for forming cup shaped articles including a reciprocating die, a member having openings therethrough and shaped to enter the formed article, means responsive to the reciprocating movement of said die to oscillate said member between a position coaxial with said die on retraction of said die and a withdrawn position on advancement of said die, and means coinciding with the withdrawn position of said member to direct an air blast into said member and outwardly through the openings therein.

2. In apparatus for forming cup shaped articles including a reciprocating die, a member in the form of a hollow truncated cone having openings in its walls, means responsive to the reciprocating movement of said die to oscillate said member between a position coaxial with said die on retraction of said die and a withdrawn position on advancement of said die, and means co-

inciding with the withdrawn position of said cone shaped member to direct an air blast into said cone shaped member and outwardly through the openings therein.

3. In apparatus for forming cup shaped articles including a reciprocating die, a shaft arranged parallel to the direction of movement of the reciprocating die, a member in the form of a hollow truncated cone having openings in its walls carried by said shaft and offset therefrom, means responsive to the reciprocating movement to oscillate said shaft to place said member in position substantially coaxial with the die on retraction of the die and to withdraw it from said position on advancement of the die, and means coinciding with the withdrawn position of said cone shaped member to direct an air blast into said cone shaped member and outwardly through the openings therein.

4. In apparatus for forming cup shaped articles including a reciprocating female die having an independently movable ejector member, a shaft arranged parallel to the direction of movement of the reciprocating die, a member in the form of a hollow truncated cone having openings through its wall carried by said shaft and offset therefrom, means responsive to the reciprocating movement to oscillate said shaft to place said cone member in position substantially coaxial with the die on retraction of the die and to withdraw it on advancement of the die, means actuated upon full retraction of the die to move the ejector member relative to the die to dislodge an article from the die, and means coinciding with the withdrawn position of said cone member to direct an air blast into said cone member and through the openings in the wall thereof to dislodge an article from said cone member.

5. In apparatus for forming cup shaped articles including a reciprocating female die adapted to retain the formed article while being retracted and an ejector member incorporated in the die and movable independently thereof, a cylindrical cam arranged parallel to the direction of movement of the die and having a slot in its wall including a relatively long straight portion and a relatively short curved portion at its rearward end, a shaft on said cam extending in the direction of the advancing movement of the die, a member bearing in said slot and reciprocating with the die, a member in the shape of a hollow truncated cone having openings through its wall fixed relative to said shaft and offset therefrom to present said cone shaped member in position substantially coaxial with the die when said bearing member is in said curved slot portion, means

actuated upon full retraction of the die to move said ejector member relative to the die to dislodge an article therefrom, and means in line with the position of the cone shaped member when said bearing member is in said straight slot portion for directing an air blast into said cone shaped member and through the openings therein.

6. In apparatus for forming cup shaped articles including a reciprocating assembly carrying a female die adapted to retain the formed article while being retracted and an ejector member incorporated in the die and movable independently thereof, a cylindrical cam arranged parallel to the direction of movement of the die and having a slot in its wall including a relatively long straight portion and a relatively short curved portion at its rearward end, a shaft on said cam extending in the direction of the advancing movement of the die, a stud secured to said reciprocating assembly and carrying a roller bearing in said slot, a member in the shape of a hollow truncated cone having openings through its wall carried by an arm fixed to said shaft to present said cone shaped member in position substantially coaxial with the die when the roller is in said curved slot portion, a pair of levers pivoted on said reciprocating assembly, a pair of plungers slidably mounted on said reciprocating assembly, pins on said ejector member in line with said plungers, air actuated means to swing said levers against said rods to move said ejector member relative to the die to dislodge an article therefrom, a valve arranged to open on full retraction of the reciprocating assembly to admit air to said air actuated means, and means in line with the position of said cone shaped member when said roller is in said straight slot portion for directing an air blast into said cone shaped member and through the openings therein to dislodge an article from said cone shaped member.
